UNITED STATES PATENT OFFICE.

CHARLES A. WENBORNE, OF CHICAGO, ILLINOIS.

DRY-KILN.

1,014,190.

Specification of Letters Patent.

Patented Jan. 9, 1912.

Application filed August 29, 1910. Serial No. 579,421.

To all whom it may concern:

Be it known that I, CHARLES A. WENBORNE, a citizen of the United States of America, and a resident of Chicago, county 5 of Cook, State of Illinois, have invented certain new and useful Improvements in Dry-Kilns, of which the following is a specification.

The main object of this invention is to 10 provide a kiln wherein substances or artificial surfaces can be exposed to the drying or oxidizing or other influence of heated air traveling horizontally, or more horizontally than vertically. Such kiln is especially 15 desirable where the substances or surfaces are fluid or viscous, or where the supports would offer too great an impediment to air traveling vertically or nearly so; also where solid materials, coated or uncoated, are of 20 such dimensions as would, in a vertically moving air current, cause eddies to form over them, and thus prevent uniformity of 25 drying or of oxidizing effect. To provide such a kiln, I have applied largely the principles underlying the form of kiln invented by myself, and patented to me April 20th, 1909, Patent No. 918,621, in which, however, the movement of the air is more vertical than horizontal, and which form of kiln is in 30 successful operation at the present time. But to make a kiln of this type work successfully with an air movement that is more horizontal than vertical, the construction must be quite different from that described 35 in my said patent.

A specific construction embodying my present invention is illustrated in the accompanying drawings, in which:—

Figure 1 is a transverse section, more or 40 less diagrammatic, of a drying kiln in which the air current in the drying chamber is substantially horizontal, and also showing an arrangement of parts which is suitable for use in connection with a series of drying 45 chambers. Fig. 2 is an enlarged sectional detail, showing the arrangement of pipes in the heating coil of the heating chamber, and also showing the shape of the deflector bars or slats, of which the partition separating 50 the heating and drying chambers is made up. Fig. 3 is a fragmentary detail in perspective, showing the construction of the partition separating the drying and cooling chambers. Fig. 4 is a detail in perspective, show-

ing the shape of the bars or slats in the 55 partition between the heating and drying chambers, and also showing the shape of the spacer blocks which are placed between these slats at their ends. Fig. 5 shows corresponding details of the slats and blocks in 60 the partition between the drying and cooling chambers.

In the form shown in the drawings, the kiln comprises a rectangular building, which has airtight walls, floor and ceiling, 65 and which has its interior subdivided by means of a second floor 1, and vertical partitions 2 and 3, to form a drying chamber A, a heating chamber B, a cooling chamber C, and return air passage D below the drying 70 chamber, connecting the cooling and heating chambers, these chambers and passage being all co-extensive with each other lengthwise of the kiln. The dimension herein referred to as the "length" of the kiln is 75 that which is at right angles to the plane of Fig. 1. Access to the drying chamber is had through a door 4, indicated in dotted outline in Fig. 1, and this door should also be capable of being closed airtight, so that 80 there can be no leakage of air through the walls of the kiln to disturb its proper operation. In the specific design shown in Fig. 1, the kiln is provided with two drying chambers A, and the heating chamber B is 85 common to both. This arrangement is not essential to the carrying out of this invention, but is shown in the drawings with the view to illustrating the manner in which a kiln having a series of drying chambers 90 might be constructed in installations where the drying chambers would be operated simultaneously and under like conditions. In most installations, it may be preferred to have each unit, comprising a drying 95 chamber A, a heating chamber B, and a cooling chamber C, independent of any of the other drying chambers.

The walls 2 and 3 are preferably built up of horizontally disposed slats supported by 100 suitable uprights and spaced apart vertically to provide long horizontal slits or air passages between them. In the form shown, the partition 2 is made up of slats 5, which are of inverted V-shape in cross-section, and 105 so assembled that the passages between them will be of tortuous form so as to prevent the radiation of heat from the heating means in

the heating chamber B to the interior of the drying chamber A. In assembling the partition 2, spacer blocks 6, shaped to fit the spaces between the slats 5, are tacked or otherwise secured to the uprights 7, and the ends of the slats 5 rest upon and are confined between the successive spacer blocks. The parts of this partition should preferably be dull black in color, and made of material of low conductivity, as for instance, wood, fiber board, asbestos composition, etc. The construction of the partition 3 is similar to that of the partition 2, with the exception that the sectional shape of the slats is determined with a view to directing the air downwardly into the cooling chamber C, rather than to cut off radiated heat. The shape of the slats 8 and spacer blocks 9 is illustrated in Fig. 5.

20 In the heating chamber B, there is arranged a steam coil 10, which comprises a series of horizontally disposed pipes connected together at their ends, to form a continuous coil extending throughout the length 25 of the chamber B. At the lower part of the chamber B, the pipes of the coil 10 are close together, and they are spaced apart at gradually increasing intervals toward the upper part of the chamber. The height to which 30 the coil 10 is carried depends upon conditions which might vary considerably in different installations, as for instance, the width of the heating chamber A, the character of the substances to be treated and the 35 range of temperature within which the kiln is to be operated, but in most cases, it is not necessary nor desirable to carry the heating coil throughout the entire height of the chamber B, for the reason that the air heated 40 by the coil tends to rise straight upward, and this tendency should be so regulated with respect to the horizontal draft induced by the cooling chamber as to insure the uniform distribution of heat throughout the drying 45 chamber, as will hereinafter appear. In most cases, it is preferred to stagger the pipes of the heating coil, as illustrated.

In the cooling chamber there is provided a condenser, comprising a system of cooling pipes which may be in the form of a coil similar to that of the steam pipes in the heating chamber, although I prefer to use a pair of horizontally disposed manifolds or headers 11 and 12, located respectively at 55 the top and bottom of the outer wall 13 of the cooling chamber, and to connect these by a series of suitably spaced vertical pipes 14. Throughout the lower part of the cooling chamber C is arranged a coil of horizontally disposed pipes 15, arranged in staggered relation to each other, and connected in succession at their ends to form a continuous coil, the outlet end being connected with the lower manifold 12, and the inlet 60 end being connected with a source of cold 65

water or other cooling medium, and controlled by a valve 16. The outlet of the cooling system is at the upper part of the chamber C, and is controlled by a valve 17. Valves 18 and 19 control the flow of heat- 70 ing medium in the heating coils 10.

The floor at 20 below the cooling coil 15 is inclined downwardly in the direction of the air current, and is provided with a gutter 21, the surfaces at each side of the gutter 21 being substantially in line with each other, so that the air flowing along them meets with no obstacle or sudden enlargement of the passage, and thus avoids the formation of eddies. 75

When there are two drying chambers A, as in Fig. 1, a low partition 22 is provided at the bottom of the chamber B to prevent conflict of the air currents entering said chamber from the two air passages D, and there is also a partition 23 which extends downward from the ceiling of the chamber B so as to separate the two air currents at the upper part thereof, which respectively 80 flow into the two chambers A. 85

The specific construction illustrated in Fig. 1, in which the kiln is made up of a series of units having common heating or drying chambers, is designed for cases where the nature of the materials to be dried permits such a construction, and this arrangement is shown merely by way of illustration, as it will be understood that in most installations, it would be preferable to have each 90 drying room independent of any other. 95

The operation of the device shown is as follows:—Before loading the kiln, it is well to turn on the steam or other heating medium for a short time, so as to warm up all of the component parts of the kiln, and have a reserve of hot air in the heating chamber. After the kiln is loaded, its door is tightly closed. Before admitting the cooling medium to the condenser, sufficient time should be allowed for the substances or surfaces to be treated to warm up to the temperature of the dry room. This time allowance will vary greatly with different substances, being dependent upon the percentage of moisture which they contain, their porosity, or in cases of coated surfaces, with the ratio of the volatile matter incorporated with the coating. Thus, with different materials to be treated, tests must be made to determine the time necessary for the preliminary warming, the time required for drying, and the temperature that can be applied most advantageously and safely. When the proper method of treatment is once determined for any one substance, it may be used as a guide for future operations, and will always produce the same results for the reason that the kiln is tightly closed, and the variable atmospheric influences on the outside cannot affect the work which is be- 100 110 115 120 125 130

ing done within. When the preliminary warming is finished, the condenser system is brought into action by starting the flow of water through it. The cold water in the condenser cools the surrounding air, which therefore contracts, and falls to the bottom of the cooling chamber C, and passes between the pipes of the coil 15 into the chamber D. The heating coil expands the air around it. This expanded air, becoming lighter, rises. In this way a circulation is set up which continues as long as the condenser is in operation. The contraction of the air in the chamber C takes place throughout that entire chamber, but is intensified at the lower part thereof by the coil 15. Thus, there is a tendency to form a partial vacuum at all parts of the condensing chamber C, which, however, is continuously off-set by the heated air flowing in to said chamber from the chamber A. This tendency creates a horizontal draft throughout the height of the chamber A, which causes the heated air from the chamber B to flow through the openings in the partition 2. The fact that the air, on becoming heated, tends to rise, insures a uniform distribution of the air current throughout the height of the partition 2, and the combined result is a tendency of the air to flow continuously in a substantially horizontal direction across the chamber A. As this influence is the same throughout the length of the chamber A, the drying action is uniform at all parts of the chamber A. The moisture, which is condensed upon the condenser through the cooling of the air in the cooling chamber, drips down on to the inclined floor 20, and runs into the gutter 40 which slopes toward one end of the kiln, and terminates in a suitable drip pipe, not shown.

The surfaces of the slats of the partition 2 are all painted a dull black, so that they will absorb instead of reflecting the heat waves, and thus radiation from the heating means into the drying chamber is prevented, and a uniform temperature throughout the drying chamber is insured. This fact also makes it possible to dry surfaces coated with varnish at an unusually high temperature without blistering the varnish.

In some cases, it may be preferred to augment the air current with certain fixed conditions, as to the temperatures of the heating and cooling chambers, and this may be accomplished by mechanical means for intensifying the draft in the passage C, and represented diagrammatically in Fig. 1 by the representation of a fan 24, which, it will be understood, is power driven.

Although but one specific embodiment of this invention is herein shown and described, it will be understood that numerous details of the construction shown may be

altered or omitted without departing from the spirit of this invention, as defined by the following claims.

I claim:—

1. A drying kiln, comprising a drying chamber, a heating chamber located at one side of said drying chamber, a cooling chamber located at the opposite side of said drying chamber, partitions separating said chambers and containing distributed apertures arranged to permit air to flow from said heating chamber to said cooling chamber in a uniformly distributed current throughout the area of said drying chamber, a return air passage connecting said cooling chamber with said heating chamber, heating means in said heating chamber, and cooling means in said cooling chamber, said heating and cooling means being located so as to produce by gravity a horizontal flow of air in said drying chamber. 70

2. A drying kiln, comprising a drying chamber, a heating chamber located at one side of said drying chamber, a cooling chamber located at the opposite side of said drying chamber, partitions separating said chambers and containing distributed apertures arranged to permit air to flow from said heating chamber to said cooling chamber in a uniformly distributed current throughout the area of said drying chamber, a return air passage connecting said cooling chamber with said heating chamber, heating means in said heating chamber, cooling means in said cooling chamber, and said partition between said heating and drying chambers being constructed to prevent the radiation of heat from said heating means into said drying chamber. 90

3. A drying kiln, comprising a drying chamber, a heating chamber located at one side of said drying chamber, a cooling chamber located at the opposite side of said drying chamber, partitions separating said chambers and containing distributed apertures arranged to permit air to flow from said heating chamber to said cooling chamber in a uniformly distributed current throughout the area of said drying chamber, a return air passage connecting said cooling chamber with said heating chamber, heating means in said heating chamber, and cooling means in said cooling chamber, said heating, cooling and drying chambers being substantially co-extensive with each other in all directions transverse to the direction of the air current in said drying chamber. 110

4. A drying kiln, comprising a drying chamber, a heating chamber located at one side of said drying chamber, a cooling chamber located at the opposite side of said drying chamber, partitions separating said chambers and containing distributed apertures arranged to permit air to flow from 120

- 4
- said heating chamber to said cooling chamber in a uniformly distributed current throughout the area of said drying chamber, a return air passage below said drying chamber, heating means in said heating chamber, and cooling means in said cooling chamber, and said partition between said drying and cooling chambers being constructed to deflect the air downwardly as it leaves said drying chamber.
5. A drying kiln, comprising a drying chamber, a heating chamber located at one side of said drying chamber, a cooling chamber located at the opposite side of said drying chamber, partitions separating said chambers and containing distributed apertures arranged to permit air to flow from said heating chamber to said cooling chamber in a uniformly distributed current throughout the area of said drying chamber, a return air passage below said drying chamber connecting said cooling chamber with said heating chamber, heating means in said heating chamber, cooling means in said cooling chamber, and said partition between said drying and cooling chambers being made up of horizontally disposed slats placed substantially in parallel relation and inclined downward toward said cooling chamber.
10. 6. A drying kiln, comprising a drying chamber, a heating chamber located at one side of said drying chamber, a cooling chamber located at the opposite side of said drying chamber, partitions separating said chambers and containing distributed apertures arranged to permit air to flow from said heating chamber to said cooling chamber in a uniformly distributed current throughout the area of said drying chamber, a return air passage below said drying chamber connecting said cooling chamber with said heating chamber, heating means in said heating chamber, and cooling means in said cooling chamber and extending substantially throughout the entire height of said drying chamber.
15. 7. A drying kiln, comprising a drying chamber, a heating chamber located at one side of said drying chamber, a cooling chamber located at the opposite side of said drying chamber, partitions separating said chambers and containing distributed apertures arranged to permit air to flow from said heating chamber to said cooling chamber in a uniformly distributed current throughout the area of said drying chamber, a return air passage below said drying chamber connecting said cooling chamber with said heating chamber, heating means in said heating chamber, and cooling means in said cooling chamber and extending substantially throughout the entire height of said drying chamber.
20. 8. A drying kiln, comprising a drying chamber, a heating chamber located at one side of said drying chamber, a cooling chamber located at the opposite side of said drying chamber, partitions separating said chambers and containing distributed apertures arranged to permit air to flow from said heating chamber to said cooling chamber in a uniformly distributed current throughout the area of said drying chamber, a return air passage below said drying chamber connecting said cooling chamber with said heating chamber, heating means in said heating chamber, and cooling means in said cooling chamber and extending substantially throughout the entire height of said drying chamber.
25. 9. In a drying kiln, the combination of a pair of drying chambers located one beside another, a common heating chamber located between them, cooling chambers located at the sides of said drying chambers opposite said common heating chamber, return air passages connecting said cooling chambers with said common heating chamber, means for heating the air in said heating chamber, and means for cooling it in said cooling chambers, partitions separating adjacent chambers and having therein distributed air passages arranged to permit the air to flow in uniformly distributed currents throughout the area of said drying chambers, the partitions between said heating and drying chambers being provided with means for preventing the radiation of heat from said heating means into said drying chambers.
30. 10. In a drying kiln of the class described, the combination of a heating chamber, a cooling chamber, a drying chamber between said heating and cooling chambers, and a return air passage outside of said drying chamber and connecting said cooling and heating chambers, a condenser in said cooling chamber, and means providing an inclined surface below said condenser and sloping downwardly from said cooling chamber toward said passage, said surface having a gutter formed therein and extending transversely to the direction of flow of the air along said surface, the parts of said surface which are at each side of said gutter being in substantial alinement with each other, whereby deflection of the air out of a direct course by said gutter will be avoided.
35. 11. A drying kiln, comprising heating, drying and cooling chambers located side by side and substantially co-extensive in the lengthwise direction, a partition separating said heating and drying chambers and having a multiplicity of air passages connecting said chambers and distributed throughout the area of said partition and being upwardly inclined from said heating chamber at their inlet ends and being downwardly

inclined toward said drying chamber at their outlet ends, and a return air passage connecting said cooling and heating chambers.

5 12. A drying kiln, comprising heating, drying and cooling chambers located side by side, a partition separating said heating and drying chambers and comprising a plurality of horizontally disposed slats of inverted trough shaped transverse section spaced apart vertically to provide air passages between them and nested one within the other, so as to prevent direct radiation of heat through said passages, and a return air passage connecting said cooling and heating chambers.

10 13. A kiln of the class described, comprising a building having heating, drying and cooling spaces located side by side, a return air passage connecting said heating and cooling spaces below said drying space, and means interposed between said heating and cooling spaces and providing a multiplicity of air passages adapted to cause the air to flow in a substantially horizontal direction

15 through said drying space, all being arranged to provide a continuous circulation of air by gravity.

14. A kiln of the class described, comprising a building having heating, drying and cooling spaces located side by side, cooling means distributed in said cooling space throughout substantially the entire height of said drying space, a return air passage connecting said heating and cooling spaces 30 below said drying space, and means interposed between said heating and cooling spaces and providing a multiplicity of air passages adapted to cause the air to flow in a substantially horizontal direction through 35 said drying space, and all being arranged to provide a continuous circulation of air by gravity.

Signed at Chicago this 27th day of August 1910.
